UNITED STATES PATENT OFFICE.

LEON DE BROUCKERE, OF BRUSSELS, BELGIUM, ASSIGNOR TO NAAMLOOZE VENNOOTSCHAP MAATSCHAPPIJ TOT VERAARDIGING VAN SNIJMACHINES VOLGENS VAN BERKEL'S PATENT EN VAN ANDERE WERKTUIGEN, OF ROTTERDAM, NETHERLANDS, A LIMITED LIABILITY COMPANY OF THE NETHERLANDS.

APPARATUS FOR ATTACHING KNIFE EDGES TO SCALE PARTS.

Application filed July 11, 1927, Serial No. 204,824, and in Belgium May 5, 1926.

This invention relates to an apparatus for attaching the fulcrum blocks or knife edges to scale beams and other scale parts, and has for its object the provision of an apparatus by which tempered fulcrum blocks may be secured to the scale parts without injuring the temper of the fulcrum blocks.

Other objects will appear from the following description.

10 The invention is exemplified in the combination and arrangement of parts shown in the accompanying drawing and described in the following specification and it is more particularly pointed out in the appended 15 claim.

In the drawing:—

Fig. 1 is a sectional view illustrating one form of apparatus for performing the present invention;

20 Fig. 2 is a view similar to Fig. 1 illustrating a second form of apparatus.

In order to secure a fulcrum block or knife edge to a scale beam or other scale part by soldering, it is necessary, of course, to apply heat to the connected parts and unless the knife edge is made of special material which is not injured by heat, there is danger that the edge will be softened. The present invention provides means for cooling the

25 fulcrum edge of the block so that it may be soldered to the scale beam without injuring the edge. This permits the use of ordinary

30 tool steel without drawing the temper from the fulcrum edge. The cooling effect may

35 be produced, according to the invention, by means of a bar or block which may be placed either on top or against the knife edge before the soldering is started. The upper apex of the knife edge may be placed

40 in a groove of the cooling block and the block may be provided with a passage for the circulation of a cooling fluid.

In the apparatus shown in Fig. 1, the numeral 10 designates a scale beam or ful-

45 crum support having a fulcrum block 11

inserted in a dove-tailed recess 12. Sufficient space is provided between the lateral faces of the fulcrum block and the sides of the recess 12 to admit the solder for securing the block to its support. A cooling block 13 is provided with a notch 14 in one side thereof which fits over the apex of the knife edge 11. The block may be provided with a longitudinal passage 15 for the circulation of a cooling medium. The passage 15 extends from one end to the other of the block and is connected with any suitable circulation system for passing the cooling medium through the opening 15.

In Fig. 2, the knife edge 11 is allowed to rest on the upper surface of a scale beam or other part 16 to which the block is to be secured. The support 16 in this case is not provided with a recess for the base of the knife edge. In this form of the invention, a cooling tube 17 is provided with a slot 18 extending longitudinally through the wall thereof and shaped to fit tightly against the side faces of the knife edge 11. The apex of the knife edge extends into the central passage 19 for the cooling medium so that the apex of the knife edge will be directly in contact with the cooling medium. The tube 17 is held by a support 20 and a coil 21 or other apparatus for supplying the electric current for soldering may be mounted on the support 20.

I claim:—

Apparatus for applying a fulcrum member to a support comprising a conduit having a slot in the wall thereof for receiving the apex of the fulcrum member, said slot being shaped to fit the lateral faces of said fulcrum member while permitting the apex of said fulcrum member to extend to the interior of the conduit.

In testimony whereof I have signed my name to this specification on this sixteenth day June A. D. 1927.

LEON DE BROUCKERE.
